FOOT REST FOR CHAIRS, SWINGS, ETC.

W. G. ZABEL.

UNITED STATES PATENT OFFICE.

WILLIAM ZABEL AND BRUNO ZABEL, OF EDGEWOOD PARK, PENNSYLVANIA.

FOOT-REST FOR CHAIRS, SWINGS, &c.

No. 922,994.

Specification of Letters Patent.

Patented May 25, 1909.

Application filed November 25, 1908. Serial No. 464,424.

To all whom it may concern:

Be it known that we, WILLIAM ZABEL and BRUNO ZABEL, residents of Edgewood Park, in the county of Allegheny and State of Pennsylvania, have invented a new and useful Improvement in Foot-Rests for Chairs, Swings, &c.; and we do hereby declare the following to be a full, clear, and exact description thereof.

10 Our invention relates to foot-rests for chairs and has special reference to a detachable foot-rest for rocking chairs, swings, etc.

The object of our invention is to provide a cheap, simple and efficient foot-rest for a 15 rocking chair which can be readily and conveniently attached to and be detached from the chair, and one which can be adjusted to the position desired when connected to the chair.

20 Our invention consists, generally stated, in the novel arrangement, construction and combination of parts, as hereinafter more specifically set forth and described and particularly pointed out in the claims.

25 To enable others skilled in the art to which our invention appertains to construct and use our improved foot-rest for chairs, we describe the same more fully, referring to the accompanying drawing, in which—

30 Figure 1 is a perspective view of a rocking chair and our improved foot-rest applied thereto. Fig. 2 is an enlarged side elevation of the foot-rest detached from the chair. Fig. 3 is an enlarged sectional view of a portion of the same and showing the foot-board connection. Fig. 4 is a like view of the connection between the carriage and supporting bar. Fig. 5 is a detail view showing the connection between the supporting bar and chair 40 hook.

Like symbols of reference herein indicate like parts in each of the figures of the drawing.

As illustrated in the drawing, 1 represents 45 the rocking chair of the ordinary construction, which is provided with the usual seat or bottom 2 therein and connected to the under face of said bottom is the foot-rest device 3, which has the attaching member 3' secured 50 to said face and preferably formed of bent wire with the horizontal hook bar 4 thereon provided with the upturned portion 4' at its free end. Detachably and pivotally connected to the hook 4 by a hole 5 at its inner 55 end is the four sided supporting bar 6, which

is suitably curved in an ogee shape, and has the vertical and downwardly extending portion 7 at its outer end for detachably fitting within a socket 8 in a vertical portion 8' extending up from the axle 9 of a carriage 10, 60 said end 7 being held within said socket by the inner face of the curved portion 7' on the bar 6 connecting said end, engaging with the upper end of the vertical portion 8' on the axle 9. The carriage 10 has the wheels 11 65 detachably connected by the cotter pins 11' at each end of the axle 9 for engaging with the floor and are preferably provided with flexible rims 12 thereon, such as rubber.

Extending above and across the supporting bar 6 is the foot-board 13, which is preferably provided with a suitable cushion 14 on its upper face and is adapted to be set at an outward and upward incline from the chair 1 when in position for use on said bar. 70 This foot-board 13 is detachably and adjustably connected to the supporting bar 6 by means of said bar passing through a U-shaped or clamp hanger 15 secured to the lower face of the said board and having holes 75 16 in the sides 17 of the same for the reception of said bar. The under face of the bar 6 is provided with a series of recesses or seats 18 therein and a pin 19 on one side of the bottom 20 of the hanger or clamp 15 is adapted 80 to engage with one of said seats and be held therein by a bent leaf spring 21 which is connected at one end to the inner side of the foot-board 13 and curved, so that its other end is turned under and toward said board 90 for bearing against the upper face of the bar 6.

When our improved foot-rest for chairs is in use, a person seated in the chair 1 and with the feet upon the board 13 will be comfortable at all times and can have the feet placed at the position desired for resting through the adjusting of said board on the bar 6, and in the movement of the said chair by rocking the wheels 11 on the carriage 10 will travel 100 backward and forward along the floor with said chair, as well as conforming to the height of the chair seat through the pivoting of said bar to the hooked member 3' on said chair.

When it is desired to adjust the foot-board 105 13 or remove the same from the bar 6, the outer side of said board can be raised to compress the spring 21 which will thereby tilt the side of the hanger or clamp 15 carrying the pin 19, and permit said pin to be released 110

from its seat 18 to allow the board to be slid along and removed from said bar, or placed at another position thereon so that upon releasing the pressure upon the said spring the 5 pin will again engage a seat and hold said board in place.

It will thus be seen that when the device 3 is assembled it can be attached to the hook 4 on the chair 1 by slipping the bar 6 over the 10 end 4' and onto said hook through the hole 5 in the inner end of said bar, and such end will hold said bar in place on said hook and enable said bar to have a slight sliding movement along said hook to permit a side movement 15 of said chair and device. The device can be readily and quickly detached from the chair 1 by passing the bar 6 over the end 4' on the hook 4 through the hole 5 in said bar and the device can be easily and rapidly 20 taken apart by removing the end portion 7 on said bar from the socket 8 on the carriage axle 9 to separate the carriage 10 from said bar, after which the pin 19 can be freed from its seat 18 on said bar, so that the foot-board 25 13 can then be slid off said bar, and thereby enable all these parts to be stored, or with the attaching member 3' for the chair 1 they can be conveniently packed for shipment.

Various modifications and changes in the 30 design, and construction of the various parts of our improved foot-rest for chairs may be resorted to without departing from the spirit of the invention or sacrificing any of its advantages.

35 What we claim as our invention, and desire to secure by Letters Patent, is—

1. The combination with a chair, of a supporting bar, a wheeled carriage connected to said bar, a foot-board, a bracket connected to 40 said foot-board, and a spring engaging with the bar to hold the bracket in engagement with the bar.

2. The combination with a chair, of a supporting bar, a wheeled carriage connected to 45 said bar, a foot-board, a bracket carried by the foot-board and engaging with one side of the bar, and a spring between the foot-

board and bar for engaging with the other side of said bar.

3. The combination with a chair, of a supporting bar connected to said chair and having seats therein, a wheeled carriage connected to said bar, a foot-board movable along said bar, and a pin on said board for engaging with said seats to adjustably secure 55 said board to said bar by a spring engaging with said bar.

4. The combination with a chair, of a supporting bar connected to said chair and having seats therein, a wheeled carriage connected to said bar, a foot-board movable along said bar, a hanger or clamp on said board and extending around said bar, and a pin on said hanger or clamp for engaging with said seats to adjustably secure said board to 65 said bar by a spring engaging with said bar.

5. The combination with a chair, of a supporting bar connected to said chair and having seats therein, a wheeled carriage connected to said bar, a foot-board movable along said bar, a pin on said board for engaging with said seats to adjustably connect said board to said bar, and a spring on said board and engaging with said bar to hold the board in position.

6. The combination with a chair, of a supporting bar connected to said chair and having seats therein, a wheeled carriage connected to said bar, a foot-board movable along said bar, a hanger or clamp on said board and extending around said bar, a pin on said hanger or clamp for engaging with said seats to adjustably connect said board to said bar, and a spring on said board and engaging with said bar to hold the board in 80 position.

In testimony whereof, we, the said WILLIAM ZABEL and BRUNO ZABEL, have hereunto set our hands.

WILLIAM ZABEL.
BRUNO ZABEL.
